UNITED STATES PATENT OFFICE.

THOMAS E. WORLINGTON, OF NEW HAVEN, CONNECTICUT.

NON-REFILLABLE BOTTLE.

SPECIFICATION forming part of Letters Patent No. 586,719, dated July 20, 1897.

Application filed April 7, 1897. Serial No. 631,093. (No model.)

To all whom it may concern:

Be it known that I, THOMAS E. WORLINGTON, a citizen of the United States, residing at New Haven, in the county of New Haven and State of Connecticut, have invented certain new and useful Improvements in Non-Refillable Bottles; and I do hereby declare the following to be a full, clear, and exact description of the invention, such as will enable others skilled in the art to which it appertains to make and use the same.

My invention relates to certain new and useful improvements in non-refillable bottles, the object being to provide improved valve mechanism within the neck thereof to control the passage of fluid therethrough and prevent refilling after the bottle has been initially filled.

To the accomplishment of this end my invention consists in valve mechanism embodying certain novel features of construction, combinations, and arrangements of parts, as will be hereinafter more fully described, and specifically set forth in the appended claim.

In the accompanying drawings, Figure 1 is a central vertical section of a bottle embodying my invention. Fig. 2 is a perspective view of the valve-chamber removed. Fig. 3 is a perspective view of a modified form of valve-chamber. Fig. 4 is a central vertical sectional view thereof; and Fig. 5 is a horizontal section through the valve-chamber, taken on a line with the spring-pressed confining projections thereof.

Like numerals designate corresponding parts throughout the several figures of the drawings.

Referring to the drawings, the numeral 1 designates the neck of a bottle provided adjoining the lower end thereof with a circumferential groove 2. The valve-chamber comprises a cylinder 3, open at the lower end thereof and formed with a reduced extremity 4 and with an interior ring-shaped flange 5, having position at the point of intersection of the cylinder and the reduced extremity of said chamber and constituting a valve-seat for a ball or spherical valve 6. The slotted reduced extremity of the valve-chamber constitutes a runway or raceway for the ball.

In order to confine the valve-chamber within the bottle-neck, I have provided the cylindric

portion 3 thereof with spring-metal locking devices 8, having one of their ends suitably secured within the said cylinder and their opposite ends provided with lateral locking projections 9, which extend through slots 10 in the cylinder and project into the circumferential groove 2 on the bottle-neck 1 and thus prevent the valve-chamber from being withdrawn. By this construction the valve-chamber cannot be withdrawn from the bottle-neck without breaking or injuring the same to such an extent that visual evidence of the bottle having been tampered with is given.

In operation it will be seen that as the reduced extremity 4 of the valve-chamber 3 is of less diameter than the neck of the bottle fluid may freely pass out through the longitudinal slots therein from the bottle-body after unseating the valve; but that if any attempt is made to refill or force fluid into the bottle the weight of the said fluid, as well as the gravity of the ball or spherical valve, causes the latter to drop to its seat and close the bottle-neck. It will thus be seen that refilling cannot take place, even should the bottle be held in horizontal position.

In Figs. 3, 4, and 5 I have shown a modified construction of valve-chamber. In this construction the cylinder 3^a of the valve-chamber is adapted to completely occupy the neck, and the reduced ball-raceway 4^a, provided with the longitudinal slots 5^a, is inclosed within the said cylinder and secured to a ring-flange 5^b therein, which forms the seat for the ball or spherical valve 6^a. Below the said ring-flange 5^b is another ring-flange 11, between which the cylinder is provided at 9^a opposite sides with slots 10^a, through which locking projections 9^a extend, which serve the same purpose as the locking projections 9 in the embodiment of the device shown in Figs. 1 and 2. In order to form a fluid-tight connection between the inner wall of the bottle-neck and the valve-chamber, the latter may be provided with suitable packing material 11^a, consisting in the present instance of a sheathing of sheet-rubber. The operation of the device thus described is precisely the same as that of the preferred form, (shown in Figs. 1 and 2,) as above stated. It is to be understood that the valve-chamber is in

serted within the bottle-neck after the bottle has been initially filled.

My invention provides a simple construction of valve device which may be manufactured at a small cost and when inserted within the bottle-neck effectually prevents refilling of the bottle.

Having thus described my invention, what I claim as new, and desire to secure by Letters Patent, is—

In a non-refillable bottle, the combination with a bottle-neck provided with an internal annular groove near its base, of a valve chamber or casing comprising a hollow cylindrical portion adapted to fit snugly in the base portion of the neck, a reduced cylindrical portion having longitudinally-extending apertures and connected to the larger portion, an intermediate ring or diaphragm connecting the larger and smaller portions of the casing

and having an opening to form a valve-seat, a ball-valve mounted loosely in the smaller portion of the casing, and spring locking devices arranged within the hollow larger portion of the casing and each consisting of a flat spring secured at one end within the casing and having its free end bent to form a catch projection which operates through an opening in the wall of the casing so as to engage in the groove in the neck, said locking devices being located within the hollow casing and above the horizontal plane of the lower edge thereof, substantially as described.

In testimony whereof I have signed this specification in the presence of two subscribing witnesses.

THOMAS E. WORTHINGTON.
